UNITED STATES PATENT OFFICE.

JOSEPH H. COCKFIELD, OF CEDAR RAPIDS, IOWA.

STONE-CRUSHER.

1,133,101.

Specification of Letters Patent. Patented Mar. 23, 1915.

Application filed May 7, 1914. Serial No. 837,056.

To all whom it may concern:

Be it known that I, JOSEPH H. COCKFIELD, a citizen of the United States, residing at 334 South Seventeenth street, Cedar Rapids, 5 in the county of Linn and State of Iowa, have invented certain new and useful Improvements in Stone-Crushers; and I do hereby declare the following to be a full, clear, and exact description of the invention, 10 such as will enable others skilled in the art to which it appertains to make and use the same.

This invention relates to grinding mills, and more especially to those employing a 15 compound movement; and the object of the same is to produce a machine which can be set to grind limestone as fine as cement or to pulverize bone and the like to such an extent that it can be dusted over the ground as 20 fertilizer, or which can be set so as to crush rocks or stones of considerable size, and which is capable of such adjustments without removing or adjusting the jaw faces.

A further object is to provide such a machine with removable jaw faces struck on a single arc so that they may be used either edge up and so that they may therefore be reversed when worn.

A still further object is to simplify the 30 construction of the entire machine as far as possible, and therefore keep its cost of manufacture and maintenance within reasonable limits.

With these and other objects in view the 35 invention consists in the general and specific details of structure hereinafter more fully described and claimed, and as shown in the drawings wherein:—

Figure 1 is a vertical sectional view of this 40 machine; Fig. 2 is an end view thereof; Figs. 3, 4, 5 and 6 are diagrams illustrating different positions of parts during a complete revolution of the main shaft.

While I do not wish to be confined to the 45 unimportant details of structure, the present embodiment of this invention includes a main frame 1 which is suitably braced to withstand the strain that is to be thrown upon it, and which is, by preference, a skeletal 50 ton structure with side plates 2 to prevent the material from dropping out between the jaws. The latter are herein numbered 3 and 4 and are duplicates, except that they are reversed because they are complementary of each other. Each has a knuckle 5 at its lower end drawn outward against a strut 6 or 7 by

means of a rod 8 or 9 connected with the jaw or its knuckle and passing outward through the frame and through a spring 10 whose tension may be adjusted as at 11. The 60 only difference in the arrangement is that the strut 6 leads upward from one knuckle 5 whereas the strut 7 leads downward from the other knuckle, and the rods 8 and 9 are or may be differently attached to the two 65 jaws at points where they will be most convenient.

Each strut is rendered adjustable in its length by any suitable means, but as best seen in Fig. 2, it is made up of overlapping 70 members 13 and 14 which may be spread apart by means of a wedge 15 and held in adjusted condition by a bolt 16, the wedge itself being held by screw or bolt 17. By this or any equivalent means, the length of 75 the strut may be increased or decreased for a purpose to appear below.

As shown in the drawings, the left-hand strut 6 leads upward from the block or bearing 5 at the lower end of the left-hand jaw 80 and its outer end rocks in a block or bearing 20 around which this strut moves so that its lower extremity travels on the arc indicated by the dotted line 21, unless the length of the strut be changed. The outer end of the 85 right-hand strut 7 turns in a block or bearing 22 carried by the frame 1 at a point below the body of this strut, and its inner end swings in an arc indicated by the dotted line 23. In other words, the left-hand strut 90 moves wholly below its point of support and the right-hand strut moves wholly above its point of support, and the purpose of this construction will be hereinafter explained.

Each jaw carries a jaw face 30 whose 95 rear wall 31 is flat and whose front wall or active face 32 is struck on a single curve from top to bottom but the radius of this curve is greater than that of either dotted line 21 or 23. The edges 33 of the removable face 30 are beveled and the lower edge rests on an undercut flange 34 extending along the lower edge of the jaw body, while its upper edge is held in place by a strip 35 underlying a shoulder 36 along the top of 105 the jaw body and held removably in place by a bolt or bolts 37. When the latter are loosened and the strip removed, it is quite obvious that the face 30 can be swung forward and lifted off the flange 34, so that it 110 can be reversed edge for edge, if the lower portion of its rounded or active face 32 has

become worn, or it can be bodily replaced by another member if it has become broken, chipped, or excessively worn. The possibility of inverting this member without interfering with the successful operation of the machine flows from the fact that the face 32 is struck on a single arc as above described.

Across the upper edge of each jaw is formed a sleeve 40 preferably carrying a bushing 41. Journaled in the main frame is a driving shaft 42 taking its power from the wheel 43 or any suitable source, and a driven shaft 44 which is rotated oppositely to and at the same speed as the driving shaft by intermeshing gears 45 and 46 of equal size. The power shaft and the driven shaft are provided with eccentrics 47 and 48 rotating within the sleeves 40 (or their bushings 41 if the latter be employed), and the peculiar setting of these eccentrics with respect to each other forms one of the important features of this invention.

I have explained the construction of the machine as best shown on Sheet 1 of the drawings, but do not wish to be confined thereto, as it is quite obvious that other means of imparting the proper motion to the edges of the jaws might be employed. Nor do I wish to be confined to the materials and proportions of parts, nor the exact details of construction set forth anywhere in this specification, as much latitude will be allowed to the manufacture in that respect. I have found by experience that where the curvature of the jaw faces is greater toward their lower edges at the point where most of the work is done, they often let down between them stones or rocks which are really beyond the capacity of the machine, and the same is broken or jammed unless it is purposely provided with weak members which break under excessive strain, and in that case the machine will have to be stopped and these members replaced. This contingency will not occur with the construction above described, besides which the jaw faces are reversible as has been explained. I find also that stone crushers employing grinding rollers or faces which move directly toward and away from each other are more apt to become clogged or broken than those wherein there is a lateral movement of one face with respect to the other. This last mentioned movement can be brought out by revolving one roller at a greater speed than the other, but the relative lateral movement is always in the same direction and at the same speed. The construction above described provides a variety of relative movements of the two jaw faces which I have found to be highly effective in crushing coarse stone or rock, in cracking fine stone or gravel, and even in reducing hard or soft stones to powder, for

which various uses my machine is adapted to be set by adjusting the length of the struts as already described.

The action which takes place is best illustrated on Sheets 2 and 3 of the drawings and may be described as follows: Beginning with Fig. 3 wherein the left jaw 3 stands raised and a line drawn from the high point 50 of its eccentric 47 and extended across its gear 45 will be almost vertical, let us assume that this line leads to the point of starting designated as 51. A similar line 60 on the right jaw 4 leads to a similar point 61, and points 55 and 65 on the two jaw faces stand opposite each other while the struts 6 and 7 are substantially parallel, although herein shown as slightly out of alignment.

In Fig. 4 the gears are shown as having turned with the arrows for a quarter revolution, so that the lines 50 and 60 are directed to the points 52 and 62. Meanwhile, the left eccentric 47 has turned so that its high point is midway between its highest and lowest positions, and therefore the left jaw and the point 55 on the face thereof have moved downward. While this was taking place, the right eccentric has moved from the position shown in Fig. 3 so that its high point has passed over its highest position and part way down the inner side, and the right jaw and its point 65 have risen slightly and commenced to travel downward. In other words, the point 55 has moved downward half of its complete throw, while the point 65 has moved upward a little and then downward about a quarter of its complete throw and is now traveling downward along with but behind the point 55. Meanwhile any points 56 and 66 on the upper part of the jaw faces have approached each other and the material between them is being crushed.

In Fig. 5 the parts have turned for another quarter revolution and the line 50 leads to the point 53 which is directly opposite the point 51, while the line 60 leads to the point 63 directly opposite the point 61. During this quarter revolution of the eccentrics, the point 55 on the left jaw has descended to its lowest limit and the point 65 on the right jaw has followed it, but has not itself yet reached its lowest limit.

In Fig. 6 the eccentrics have made another quarter revolution, the lines 50 and 60 have passed around so that they are directed toward the points 54 and 64 respectively, and the point 55 has traveled half-way up its stroke, while the point 65 has descended to the lowest extreme of its movement and started upward. But while the crank motion imparted to the upper edges of the jaws by the eccentrics on the rotating shafts has caused those jaws to rise and fall to the same extent, the swinging motion

imparted to the lower edges of said jaws by the struts 6 and 7 has caused those edges to travel on the dotted arcs 21 and 23, the former of which is through a path below 5 the pivot 20 of its strut and the latter of which is through a path above the pivot 22. Therefore, the lower edge of the left jaw swung downward and outward from an upright medium line between the jaws, while 10 the lower edge of the right jaw swung downward and inward and across said line; and then both lower edges ascended along their respective arcs. The result is that the active faces have been in contact throughout 15 the movement thus far described, but the point 55 has descended lower than the point 65. Therefore at this time, when the parts stand as seen in Fig. 6, the points 55 and 65 are opposite each other and both are ascending. 20 Meanwhile the upper portions 56 and 66 of the jaw faces have been moving apart for the reception of more material which is being fed into the machine at the top.

Through the next quarter revolution the 25 parts move back to the position shown in Fig. 3, and then the operation is repeated. Manifestly the speed of movement of the points 55 and 65 would be changed somewhat if the rotation were in a direction 30 opposite to that indicated by the arrows, but we need not go into this matter. Obviously also, the distance between the active faces 32 of the two jaws may be adjusted by adjusting the length of the struts 6 and 7, although 35 so long as the lower edges of the jaws swing about the pivot points 20 and 22 the action above described will take place. Adjustment in the length of said struts is for the purpose of changing the function 40 of the machine. If large rocks or stones are to be broken up, the active faces are set at that distance apart which the diameter of the broken pieces is to be. If the desire is to crush stones or pebbles, the faces will 45 be set closer together. And it is quite possible with this machine to pulverize or powder stone or bone as first mentioned above. It is not usual to reduce large stones to powder at one operation, and if this is done 50 great strain is thrown on the machine. In any event, however, the lower portion of the active faces 32 will eventually become worn, and in that case the jaw faces can be detached and inverted, *i. e.*, reversed edge for 55 edge. The side plates 2 prevent the material from working out at the ends of the jaws when the machine is in operation. I have not considered it necessary to show any feed mechanism or hopper, nor any discharge mechanism or chute.

What I claim is:

1. A crusher embodying jaws diverging upward and having opposed coacting curved faces, means for imparting crank motion to 60 the upper edges of said jaws, and means

for permitting the lower edges of said jaws to move up and down on arcs struck around centers respectively above and below a horizontal line through the lower edges of the jaws.

2. A crusher embodying jaws having opposed curved faces, means for imparting crank motion to their upper edges on opposite sides of an upright median line between them, and struts connected with the lower edges of said jaws and leading outward from them to pivotal points respectively above and below a horizontal line drawn at right angles to said median line.

3. A crusher embodying jaws having opposed faces struck on opposite curves, means for imparting crank motion to their upper edges, struts connected with their lower edges and leading outward from them to pivotal points respectively above and below a horizontal line through said lower edges, 85 means for permitting adjustment in the length of said struts without altering their said pivotal points and yielding means tending to draw said lower edges normally 90 apart.

4. A crusher embodying jaws having opposed faces struck on opposite curves whereof each is part of a circle, means for imparting crank motion in opposite directions and 95 at the same speed to their upper edges, knuckles in rear of their lower edges, a framework having bearings behind said jaws and whereof one is above and the other below a horizontal line through said 100 knuckles, a strut mounted at its outer end in each bearing and having its inner end resting in the nearest knuckle, and means for pressing each knuckle toward its strut.

5. In a crusher, the combination with a 105 framework having bearings in its upper portion, a power shaft and a driven shaft mounted in said bearings, eccentrics fast on said shafts, and two jaws having their upper edges embracing said eccentrics and their faces struck on opposite curves; of bearings in the lower portion of said framework behind the jaws and respectively above and below a horizontal line through their lower edges, a strut pivotally connecting 110 each bearing with the lower edge of the nearest jaw, and means for permitting the adjustment of the length of each strut.

6. In a crusher the combination with a framework having bearings in its upper portion, a power shaft and a driven shaft mounted in said bearings and connected by gears of equal size, eccentrics fast on said shafts, substantially upright jaws having sleeves at their upper edges embracing said 120 eccentrics, and wear faces to the jaws struck on opposite curves; of bearings in the lower portion of said framework behind the jaws and respectively above and below a horizontal line through their lower edges, and 130

4
swinging members each connecting one of said bearings with the lower edge of the nearest jaw.

7. In a crusher the combination with a framework having bearings in its upper portion, a power shaft and a driven shaft mounted in said bearings and connected by gears of equal size, eccentrics fast on said shafts, substantially upright jaws having sleeves at their upper edges embracing said eccentrics, and wear faces to the jaws struck on opposite curves; of bearings in the lower portion of said framework behind the jaws and respectively above and below a horizon-

tal line through their lower edges, a strut 15 pivotally connecting each bearing with the lower edge of the nearest jaw, means for permitting the adjustment of the length of each strut, and a spring-actuated rod connecting the framework with each jaw and 20 tending to draw the latter outward.

In testimony whereof I affix my signature in presence of two witnesses.

JOSEPH H. COCKFIELD.
